UNITED STATES PATENT OFFICE.

FREDERICK C. BREAKSPEAR, OF CHICOPEE, MASSACHUSETTS, ASSIGNOR TO A. G. SPALDING & BROS., OF JERSEY CITY, NEW JERSEY, A CORPORATION OF NEW JERSEY.

DESIGN FOR A GOLF-BALL.

42,164.

Specification for Design.

Patented Feb. 13, 1912.

Application filed November 22, 1911. Serial No. 661,872. Term of patent 7 years.

To all whom it may concern:

Be it known that I, FREDERICK C. BREAKSPEAR, a citizen of the United States, residing at Chicopee, in the county of Hampden and State of Massachusetts, have invented a new, original, and ornamental Design for Golf-Balls, of which the following is a specification, reference being had to the accompanying drawing, forming a part hereof.

The figure is a view in elevation of a golf ball, showing the new design.

I claim:

The ornamental design for a golf ball, as shown.

This specification signed and witnessed this 17th day of November, A. D. 1911.

FREDERICK C. BREAKSPEAR.

Signed in the presence of—

HOWARD L. HOLT,
CLARENCE H. ARCHER.
